(57) **CLAIM**

The ornamental design for an LED troffer as shown and described.

DESCRIPTION

FIG. 1 is a front, perspective view of an LED troffer showing our new design;

FIG. 2 is a front view of an LED troffer;

FIG. 3 is a rear view of an LED troffer;

FIG. 4 is a left side view of an LED troffer;

FIG. 5 is a right side view of an LED troffer;

FIG. 6 is a top plan view of an LED troffer; and,

FIG. 7 is a bottom plan view of an LED troffer.

The broken lines shown in the drawings represent unclaimed portions and elements of the LED troffer that form no part of the claimed design.

1 Claim, 4 Drawing Sheets
